UNITED STATES PATENT OFFICE

JACOB TELLER, OF CHICAGO, ILLINOIS, AND ARTHUR P. SCHULZ, OF BUFFALO, NEW YORK, ASSIGNORS TO TELLER CORPORATION, OF CHATTANOOGA, TENNESSEE, A CORPORATION OF TENNESSEE

DESIGN FOR A CLOSED-TOP CABINET GAS, ELECTRIC, OR OIL RANGE

Application filed November 26, 1930. Serial No. 37,801. Term of patent 7 years.

To all whom it may concern:

Be it known that we, JACOB TELLER, a citizen of the United States, and a resident of Chicago, in the county of Cook, State of Illinois, and ARTHUR P. SCHULZ, a citizen of the United States, and resident of Buffalo, in the county of Erie and State of New York, have invented a new, original, and ornamental Design for a Closed-Top Cabinet Gas, Electric, or Oil Range, of which the following is a specification, reference being had to the ac-

companying drawing, forming a part thereof.

Figure 1 is a front perspective view of the range;

Fig. 2 is an end view thereof; and

Fig. 3 is a perspective view showing the lid in the open position.

We claim:

The ornamental design for a closed-top cabinet gas, electric, or oil range, as shown.

JACOB TELLER.

ARTHUR P. SCHULZ.
